UNITED STATES PATENT OFFICE.

JAMES S. COPELAND, OF HARTFORD, CONNECTICUT, ASSIGNOR TO THE
POPE MANUFACTURING COMPANY, OF SAME PLACE.

DESIGN FOR A REAR BRACKET FOR BICYCLES.

SPECIFICATION forming part of Design No. 26,981, dated April 27, 1897.

Application filed March 11, 1897. Serial No. 627,066. Term of patent 14 years.

To all whom it may concern:

Be it known that I, JAMES S. COPELAND, a citizen of the United States, and a resident of Hartford, in the county of Hartford and State of Connecticut, have invented a new and original Design for a Rear Bracket for Bicycles; and I do hereby declare the following, when taken in connection with the accompanying drawings and letters of reference marked thereon, to be a full, clear, and exact description of the same, and said drawings constitute part of this specification, and represent, in—

Figure 1, a view in rear elevation of the bracket; and in Fig. 2, a view in side elevation, or what may be termed the "front" of the bracket.

My invention relates to a design for a bracket which forms part of the frame at the rear of the bicycle and adjacent to the rear driving-wheel axle; and said invention consists in the configuration of the structure, as hereinafter described, and shown in the accompanying drawings.

The bracket has a main portion *a* of cylindrical form in general outline when viewed from the rear in the line of the axis of the cylinder, the rear of this body part having substantially flat surfaces *b* *c* at the upper

and lower portions, respectively, with an oval or semicylindrical portion *d* joining the flat surfaces and extending transversely across what may be termed the "head" of the body part. This rounded central portion *d* extends into a cone-shaped enlargement *e*, which is rounded in a plane parallel to the plane of the axis of the body part *a*.

A tubular extension *f* projects from the front of the body part *a* and is reduced in diameter toward its outer end.

The essential feature of my invention is the cylindrical body part, with a flattened back portion formed in sections united by a rounded part, in connection with a conical or flaring lateral projection on the side of the body part.

45
I claim—

The design for a rear bracket for a bicycle-frame, substantially as shown.

In testimony whereof I have signed this specification in the presence of two subscribing witnesses.

JAMES S. COPELAND.
